US00D814545S

(12) **United States Design Patent** (10) **Patent No.:** **US D814,545 S**
(45) **Date of Patent:** **** Apr. 3, 2018**

(54) **HANDLE FOR CAMERA OR THE LIKE**

(71) Applicant: **SZ DJI Osmo Technology Co., Ltd.**,
Shenzhen (CN)

(72) Inventors: **Min Kim**, Shenzhen (CN); **Zhen Wang**, Shenzhen (CN); **Haibin Zheng**, Shenzhen (CN)

(73) Assignee: **SZ DJI Osmo Technology Co., Ltd.**,
Shenzhen (CN)

(**) Term: **15 Years**

(21) Appl. No.: **29/575,754**

(22) Filed: **Aug. 29, 2016**

Related U.S. Application Data

(63) Continuation of application No. 29/540,667, filed on Sep. 25, 2015.

(57) **CLAIM**

The ornamental design for a handle for camera or the like, as shown and described.

DESCRIPTION

FIG. 1 is a front perspective view of a handle for camera or the like showing the claimed design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top thereof; and,

FIG. 8 is a bottom view thereof.

The broken lines in the figures show portions of the handle for camera or the like that form no part of the claimed design.

1 Claim, 8 Drawing Sheets
